United States Patent Office

Des. 194,492
Patented Jan. 29, 1963

194,492

CONFECTION

Isadore Herman, 1040 5th Ave., New Kensington, Pa.

Filed Mar. 21, 1962, Ser. No. 69,357

Term of patent 14 years

(Cl. D82—2)

FIG.1

FIG.2

FIG.5

FIG.3

FIG.4

FIGURE 1 is a front elevational view of a confection, showing my new design with part of the stick being shown broken away for convenience of illustration;

FIGURE 2 is a rear elevational view thereof;

FIGURE 3 is a side elevational view thereof as seen from the left side in FIGURE 1;

FIGURE 4 is a side elevational view thereof as seen from the right side in FIGURE 1; and

FIGURE 5 is a top view thereof.

The essential features of the design reside in the portions shown in full lines on the drawing.

I claim:

The ornamental design for a confection, as shown and described.
